CUSHION FILLING MACHINE

David Lochner, Fort Wayne, Ind., assignor to Lochner Mfg. Co., Fort Wayne, Ind., a copartnership of Indiana

Application December 18, 1950, Serial No. 201,450

15 Claims. (Cl. 53—257)

This invention is directed to a machine for introducing 15 a filler into the cover or casing of a cushion.

Various types of machines for this purpose now in commercial use have not proven entirely satisfactory or efficient under all operating conditions. Some of the larger machines are cumbersome and heavy and take up considerable valuable floor space, which is not always available in upholstery shops of medium or average size. Many of these larger machines are also complicated and include a multitude of shafts, belts, pulleys, and belt shifting devices, while others include numerous gear trains, cam arrangements and intricate clutch mechanisms. These machines require frequent adjustments and considerable expense is necessary to maintain them in good working order. Moreover, some of these machines are dangerous to operate and difficult to control. Also, some machines are so fragile, light in weight, and unstable in construction that they fail in operation when subjected to hard continuous use.

One of the principal objects of the invention is to provide a machine which overcomes all of the disadvantages inherent in the machines above referred to.

An important object of the subject invention is to provide a substantial machine embodying improved principles of design and construction and which is primarily designed for installation and use in shops of medium or average size.

Another object is to provide a sturdy machine in which the various movable components thereof are so arranged with respect to one another that they are well balanced and supported for efficient and smooth operation.

Another object of the invention is to provide a machine having a cushion box embodying a pair of side sections which are relatively adjustable in a novel manner whereby the width of the box may be varied as desired.

An additional object of the invention is to provide a unique ram assembly and improved means for supporting, guiding and operating it, the arrangement being such that an operator can use both hands to adjust and hold a cushion cover in proper relationship to the box while the filler material is being fed and packed into the cover by the ram.

A further object of the invention is to provide a novel foot operated treadle, unique clutch means and improved means for operatively connecting the clutch means with the ram assembly.

A significant object of the invention is to provide a machine in which the improved means for supporting and guiding the ram assembly includes a pair of supports which carry rotatable bearings for an elongated rack bar constituting a component of the ram assembly.

A particular object of the invention is to provide a construction in which each support includes a pair of standards with means interposed between the standards for reinforcing and maintaining them in predetermined parallel relation.

An important object of the invention is to provide a unique pawl carried by one of the supports above re-

2

ferred to for automatically operatively engaging and locking the ram assembly in place as it is progressively projected forwardly by the clutch means when the treadle is operated. In other words, when the ram assembly is moved forwardly to a predetermined position in packing filler material into a cushion cover the pawl will hold the assembly in such position until it is again directed forwardly, and so on.

Another important object of the invention is to provide an arrangement whereby the pawl will be automatically rendered inoperative after the cushion cover has been properly filled in order to permit the ram assembly to be retracted or moved back to a starting position.

A still further object of the invention is to provide a machine which is efficient, positive in action, and comprised of components which can be economically manufactured and readily assembled on a production basis to such an extent that it can be sold at a reasonable price.

Many other objects and advantages of the invention will become apparent after the description hereinafter set forth is considered in connection with the drawings annexed hereto which exemplify one embodiment of the invention.

In the drawings wherein like or corresponding parts or elements are identified by the same numerals:

Figure 1 is a top view of the cushion filling machine embodying the invention, with portions of the machine broken away to illustrate certain details of construction;

Figure 2 is a side view in elevation of the structure depicted in Figure 1, with portions broken away to show other details;

Figure 3 is an enlarged transverse section taken substantially on line 3—3 of Figure 2 showing details of the cushion box and some of the linkage assembly;

Figure 4 is a transverse section taken substantially on line 4—4 of Figure 2 depicting additional details of the linkage assembly;

Figure 5 is a perspective view of a portion of a means for operating the side units of the cushion box;

Figures 6 and 7 are enlarged top and side views of portions of the machine showing the arrangement of the standards and the manner of supporting the rack bar of the ram assembly thereon, including the relationship of the clutch means and pawl with the rack bar;

Figures 8 and 9 are partial side views of the machine illustrating the rearmost position and an intermediate forward position of the ram assembly and the operative relationship of the pawl;

Figures 10 and 11 are partial side views of the machine illustrating the foremost forward position and an intermediate rearward position of the ram assembly and the operative relationship of the pawl;

Figure 12 is an enlarged side view of the pawl;

Figure 13 is an end view of a modified composite form of pawl;

Figure 14 is a perspective view of the linkage assembly which is employed to operatively connect the clutch means with the foot treadle; and

Figure 15 is an elevational view looking in the direction of the arrows 15—15 in Figure 14.

The machine exemplified in the drawings includes, among other things, a substantial stand generally designated 1, an elongated rectangular open ended cushion or stuffing box 2, means including a hand wheel 3 whereby the width of the box may be adjusted to accommodate cushion covers of various sizes, a ram or plunger assembly 4, clutch or actuating means 5 operatively connected to the ram assembly, and a treadle 6 operatively connected to the clutch means 5 by a linkage assembly, all of which will be described more in detail subsequently. The stand 1 may be designed and constructed as de-

sired, but as herein illustrated, preferably includes a pair of front legs 7 and 8 and a pair of rear legs 9 and 10 which are trussed together in a manner to impart strength and stability to the structure. The upper ends of the front legs 7 and 8 are joined by a transverse front rail 11 and the upper ends of the rear legs 9 and 10 by a similar rear rail 12. The upper end of the front leg 7 is joined to the upper end of the rear leg 9 by a longitudinal rail 13 and the upper ends of front leg 8 and rear leg 10 by a similar rail 14. It will be noted that the front and rear legs are inclined and that the legs at one side of the machine are parallel to the legs at the other side. The legs and other components of the machine, where strength, rigidity and economy are required, are preferably made of angle iron. The lower end of each leg is provided with a foot 15 having an aperture therein through which a screw may be extended into a floor for firmly anchoring the machine in place.

A relatively narrow elongated platform or table comprised of a pair of longitudinal angle iron members 16 and 17 is secured to the stand and extends rearwardly thereof preferably on a level below that of the cushion box 2. The members 16 and 17 are arranged in spaced apart parallel relationship and are attached to the underside of transverse rails 11 and 12 by fastening means 18 as shown in Figures 3 and 4. A pair of corresponding standards 19 are respectively attached to the outer rear ends of the table members 16 and 17 and a pair of corresponding standards 20 are attached to the members 16 and 17 at a point spaced forwardly of the rear standards 19. These standards support and guide a rack bar 21 of the ram assembly 4. Each standard is provided with a relatively large base flange. Bolts 22 extend through these flanges and through the members 16 and 17 for firmly detachably connecting the standards thereto. These supporting and guiding standards for the ram assembly and other components related thereto will be alluded to more in detail subsequently.

The novel cushion or stuffing box 2 and the unique manner of mounting it on the stand 1 will now be described. The box may be mounted in various ways but as herein depicted it is preferably supported so that its forward free extremity projects a sufficient distance in advance of the stand 1 to enable an operator to conveniently operate the machine and otherwise have the full use of both hands to do whatever is required with respect to properly filling a cushion cover.

More particularly, the movable side units or assemblies of the box above referred to are mounted on a pair of parallel round guide rods 23 for movement in planes transverse to the longitudinal axis of the cushion box. The ends of the rods are anchored in blocks 24 carried by the side rails 13 and 14 of the stand as shown by the dotted lines in Figure 1. As shown in Figure 4, the box includes a flat center bottom wall 25 which is supported in a fixed position on the transverse rails 11 and 12 of the stand by a bolt 26. This bolt extends through the rail 11, through a spacer 27 interposed between the rail and center wall 25, and also downwardly between the table members 16 and 17. A washer 28 bears against the members 16 and 17 and a nut 29 on the bolt firmly secures the wall 25 in a predetermined horizontal position above the cross rail 11. The rear extremity of the center wall 25 is secured to the rear cross rail 12 by a bolt 26a shown in Figure 3, with a spacer corresponding to spacer 27 interposed between the rail and wall.

As clearly depicted in Figure 3, each of the movable side units or sub-assemblies of the cushion box includes a side wall 30 provided with an integral inturned horizontal planar wall 31 which complements the center wall 25 to provide a sectional bottom or platform for the filler material. The inturned walls 31 are arranged to slidably engage the underside of the center wall substantially throughout its entire length and thereby lend support to its forwardly extending extremity in advance of the stand.

A pair of covers are respectively hinged to the side walls 30. Each cover includes a relatively large rectangular flat portion 32 and an angular portion 33. The angular portions constitute continuations of the side walls 30. It will be noted that the flat portion of one cover overlaps the flat portion of the other cover when the box is closed as illustrated in Figures 1 and 3. More particularly in this regard, the combined widths of the covers is greater than the full open width of the box so that under normal operating conditions the covers will always be maintained in an overlapping relationship when the box is closed. Thus, it will be evident that a side wall and its inturned wall and an attached cover constitute a separate unit or sub-assembly of the box.

As clearly shown in Figures 1, 2, 3 and 5, a relatively heavy and strong bracket is secured to each side assembly of the cushion box. Each bracket includes an upstanding portion 34 secured exteriorly to a side wall 30 of the box by bolts 35 and an inturned elongated portion 36 which is secured to the underside of each inturned planar wall 31 of the box by a screw 37. Each bracket is further provided with two pairs of integral apertured bearings 38 which slidably receive the guide rods 23. A threaded shaft 39 is interposed between the guide rods 25 and its ends are journalled in the blocks 24 carried by the side rails 13 and 14 of the stand. The opposite extremities of the shaft are provided with left and right handed threaded portions 40 and 41 as shown in Figures 1 and 5. A nut 42 is carried by each of the threaded portions, and each nut is interposed and trapped between a pair of generally U-shaped lugs 43 carried by each bracket. The shaft 39 extends through the lugs 43. The arrangement is such that rotation of the shaft 39 by the hand wheel 3 at the right side of the machine will cause the side assemblies or units of the cushion box to move simultaneously toward or away from the fixed or stationary center bottom wall 25 so that the width of the box may be varied as desired to accommodate cushion covers of different sizes.

An elongated member 44, clearly shown in Figure 3, is firmly secured to the upper cover of the box by rivets 45 and its free end is adapted to directly engage a pivotal latch 46 mounted on one of the brackets for holding the covers in place while a cushion cover is being packed with filler material.

Referring again to the supports for the rack bar 21, a spacer bearing block 47 is preferably secured by welds between the upper ends of the rear standards 19 and a spacer block 48 is secured by welds between their lower ends and between the longitudinal table members 16 and 17 by a bolt 49. The upper block 47 is provided with a lower horizontal marginal edge 50 and the lower block 48 with an upper horizontal marginal edge 51 spaced from edge 50. It is through this space that the rack bar 21 reciprocates. A spacer bearing block 52 is preferably secured by welds between the upper ends of the front standards 20 and a lower block 53 is similarly secured between the lower ends of the standards and between the table members 16 and 17 by a bolt 54. The bolts 49, 54 and 22 permit detachment of the standards from the table members for replacement purposes. The opposed inner horizontal marginal edges of blocks 52 and 53 also define a space through which the rack bar reciprocates.

A shaft 55 extends transversely through the front standards 20 and rotatably supports a roller 56 mounted on a sleeve bearing. A shaft 57 is carried by the rear standards 19 and supports a corresponding roller 58 mounted on a sleeve bearing. The arrangement is preferably such that the distance between the marginal edge 50 of the upper spacer block 47 and the periphery of roller 58 substantially corresponds to the distance between the lower marginal edge of block 52 and roller 56, such distances being slightly greater than the width of the rack bar 21 to provide guideways for the bar. The distances between the table members are primarily determined by the lower

blocks 48 and 53 and also by additional spacers, one of which is indicated at 59 in Figure 3 to hold the forward and intermediate portions of the table members 16 and 17 in parallel relation. With this setup the standards serve to support and accurately guide the bar and a pressure plate 60 carried thereby in a straight forward and rearward direction. The rack bar 21 is preferably supported so that the lower edge of the pressure plate does not engage the center bottom wall 25 of the cushion box. This arrangement and the rollers constituting anti-friction means materially reduce friction and ease the reciprocatory movement of the ram.

The locking mechanism for the ram assembly constituting a novel feature of the invention will now be described. It will be noted that the upper block 47 carried by the rear standards 19 is offset rearwardly to some extent in order to provide a clearance space for a locking mechanism, preferably in the form of a pawl 61 which is pivoted on a replaceable pin 62, the latter extending through the rear standards 19 as shown in Figures 6 and 7.

The pressure plate 60, above referred to, is secured to the front end of the bar at right angles thereto and carries a stop 63. The rear end of the bar carries a bolt 64. Forward movement of the ram assembly is limited by the bolt 64 engaging the rear standards 19 and its rearward movement is limited by the stop 63 engaging the front standards 20. Obviously, other means may be employed to determine the travel of the ram assembly. Attention is directed to the fact that the lower cover of the cushion box finds support on the upper edge of the pressure plate.

The lower longitudinal edge of the rack bar is continuous and smooth for engagement with the rollers 56 and 58 but its upper edge is provided with a plurality of abutments, preferably in the form of arcuate notches 65, the centers of which are spaced equal distances apart throughout substantially the full length of the bar. The notches are adapted to individually receive a rounded nose portion 66 of the pawl for successively locking the ram assembly in position as it is progressively advanced forwardly by the treadle 6 through the agency of the clutch or actuating means 5. The upper edge of the bar is also provided with a relatively large arcuate clearance recess 67 located forwardly of the notches 65 and a corresponding large recess 68 located rearwardly of the notches 65.

The pawl 61 is preferably made by striking it out from thick sheet metal stock and is preferably so designed, constructed and supported that its nose portion 66 will normally bear or engage the rack bar at all times except when in the recesses 67 and 68. The pawl is freely pivotal and of such a thickness that it is to some extent guided by the standards 19. Attention is directed to the fact that the pawl 61, recess 68 and bolt 64 are so positioned with respect to one another that when the bolt engages the rear standards 19 at the termination of the forward stroke of the ram assembly, the nose portion 66 of the pawl will fall into the clearance recess 68 as shown in Figure 10, and thereby render the pawl inoperative so that the ram assembly can be readily manually retracted or pushed back to a starting position. The pawl, recess 67 and the stop 63 on the pressure plate 60 are also so arranged that when the stop 63 engages the front standards 20 to determine the termination of the rear stroke of the ram assembly, the nose portion 66 will fall into the clearance recess 67, and thereby place the pawl in position to successively engage any of the notches 65 desired as the ram assembly is directed forwardly step by step by the clutch and treadle.

If found desirable, the pawl 61 clearly illustrated in Figure 12 may be comprised of a plurality of stampings as shown in Figure 13, each stamping, when in use, being freely pivotal.

The clutch or actuating means 5, above referred to, may be designed and constructed as desired, but preferably includes a pair of corresponding rectangular plates 69 as depicted in Figure 7. A spacer 70 is secured be-

tween the upper ends of the plates by rivets 71 and the lower extremities of the plates are secured by a pin 72. The lower marginal edge of the spacer finds support on the upper edge of the rack bar. A removable pivot 73 is secured to the plates and supports a lever 74. Movement of the lever in one direction is limited by the pin 72, as shown in Figure 7. A shaft 75 bridges the plates and supports a roller 76 therebetween. The periphery of this roller is aligned with the peripheries of rollers 56 and 58 and is engageable with the lower edge of the rack bar 21. The upper end of the lever is preferably provided with a roller bearing 77 rotatably held in an arcuate recess of corresponding cross-section in the lever and by the plates 69. The periphery of the bearing 77 is adapted to intermittently engage the lower longitudinal edge of the bar 21 and press the upper edge of the bar against the spacer 70 and thereby exert a clamping action to carry the ram assembly forwardly along with the clutch when the treadle 6 is depressed. This roller bearing 77 reduces friction between the lever and bar on the return stroke of the clutch and also provides a good gripping action in combination with the other related cooperating components of the clutch means. The clutch means is carried by the rack bar and as clearly illustrated the upper portion 25 of the lever 74 is guided by the plates 69 and its lower portion is arranged for guidance between the table members 16 and 17. The arrangement is preferably such that the standards 19 and 20 also serve to limit or determine the travel of the clutch means.

30 The unique linkage assembly, clearly illustrated in Figures 2, 14 and 15, operatively connecting the lever 74 and the treadle 6, will now be described. A pair of outer strap hangers 78 have their upper ends fixedly attached to and exteriorly of the depending parallel portions of the table members 16 and 17 by means of a bolt 79 which extends through the hangers, the table members, and the spacer 59 above referred to. A second pair 35 of strap hangers 80 of a greater length than hangers 78 have their upper ends fixedly attached to and exteriorly of the depending parallel portions of the table members by a bolt 81. A spacer 82 corresponding to spacer 59 is carried by the bolt 81 to assist in maintaining the table members 16 and 17 parallel. The lower ends of the long hangers 80 overlap the exterior surfaces of the lower ends of the short hangers 78. A replaceable king pin 83 extends through and connects the lower ends of the hangers together. These hangers provide a stable support for a generally triangular frame generally designated X. The lower corner of frame X is pivoted on the king pin 83. The inner ends of a pair of elongated links 84 are pivotally connected by a removable pin 85 to the right corner of the frame and the outer ends of these links are pivotally connected to the lower end of the clutch lever 74 by a removable pin 86. The upper 50 ends of a pair of links 87 are pivotally connected to the left corner of the frame X by a removable pin 88 and the lower ends of these links are pivotally connected to a fitting 89 on the treadle by a bolt or pin 90 as shown in Figure 2.

60 The frame X may be designed and constructed as desired but is preferably comprised of a plurality of members constructed from steel strip stock of sufficient strength for the purpose intended. More particularly, the upper side of the frame includes a pair of corresponding members 91, the left side a pair of corresponding members 92, and the right side a pair of corresponding members 93 which engage one another. The frame X and links 84 are arranged for movement and guidance between the hangers 78 and 80. The pairs of members 91 and 92 are preferably of the same length to promote standardization of parts and economy in construction. The inner ends of the links 84 straddle the upper ends of members 93 and the rear ends of members 91 straddle members 93. The forward ends of members 91 straddle 65 the forward ends of members 92 and the upper ends of

links 87 straddle members 91. The rear ends of members 92 straddle the lower ends of members 93, the lower ends of hangers 78 straddle the rear ends of members 92 and the lower ends of hangers 80 straddle the lower ends of hangers 78.

The treadle generally designated 6 includes an elongated lever 94. The rear end of the lever is pivotally connected to rear leg 9 of the stand by a bolt 95 as shown in Figure 1. Its outer end is provided with angle pieces 96 welded thereto to form a pressure pedal adapted to be engaged by the foot of the operator. This lever extends diagonally through the machine with the pressure pedal located at a convenient place for operation at the front end and right side of the machine so that the treadle can be operated while manipulating the hand wheel 3. A diagonal brace 97 assisting to locate the lever 94 has one end pivotally connected at 98 to the rear leg 10 of the stand and its other end is fixedly connected to the treadle at a point intermediate its ends. A relatively strong helical spring 99 has its upper end hooked in the table member 16 as shown in Figure 1 and its lower end hooked in the brace 97 to cause the forward ends of the frame members 91 to bear against the washer 28 and normally maintain the clutch more or less in abutting relationship with the rear standards 19 as illustrated in Figures 1, 2, 6 and 7 and the treadle in the position shown by the full lines in Figure 2.

To operate the machine is a relatively simple matter. The procedure may vary in some instances but is preferably accomplished by first swinging the covers of the cushion box outwardly to a full open position, manipulating the hand wheel 3 to move the side units of the box outwardly on the guide rods 23 to increase the size of the box to its maximum width, manually retracting the ram assembly, placing filler in the box, closing and fastening the covers, turning the hand wheel 3 to compress the filler and determine the width of the box for a cover of a given dimension, and then operating the treadle. When the treadle is depressed the clutch 5 will grip the rack bar 21 and force the ram forwardly to cause the pressure plate 60 to pack the filler material into the cover. When the treadle is first depressed the nose 66 of the pawl 61 will automatically ride out of the clearance recess 67 and when the treadle is released the nose 66 will come to rest in one of the notches 65 to prevent rearward movement of the ram assembly due to back pressure or resistance offered by the compressed filler material. Releasing the treadle will cause the helical spring 99 to return the clutch back to its normal position as shown in Figures 1, 2, 6 and 7. With this setup the ram assembly can be readily advanced forwardly any distance desired by operating the treadle and automatically held by the pawl 61. When the ram assembly has been moved forwardly to its full limit of travel determined by the bolt 64 engaging the rear standards 19, the nose of the pawl 61 will fall in the arcuate recess 68 to render the pawl inoperative, whereupon the ram assembly can be manually returned to a starting position. When the ram assembly is again directed forwardly, the pawl will become automatically operable to hold the ram assembly in any forward position of travel. The foregoing arrangement has proven very satisfactory in use under all operating conditions. The locking mechanism for the ram assembly is simple, efficient, entirely automatic and is exposed and so constructed that fibers or lint from the filler material and covers will not accumulate in the mechanism and interfere with its operation. More particularly in this respect, movement of the pawl is preferably accomplished by designing and supporting it so that it will swing into any notch—no spring or other mechanism or adjustment is required to forcibly urge the pawl into any of its positions.

Accordingly, it should be manifest that I have pro-

vided a machine possessed of many novel attributes for accomplishing the objectives above set forth.

Having thus described my invention, it will be obvious that it is susceptible of various modifications, and that the claims appended hereto determine the scope of the subject invention, notwithstanding the foregoing detailed description.

I claim:

1. A filling machine comprising a stand, a box carried by the stand, a platform carried by the stand and located at a level below that of the box, a pair of supporting means mounted on the platform, each of said supporting means comprising a pair of closely related members, anti-friction means confined between the members of each supporting means, a ram carried by the anti-friction means and guided by said members, and clutch means carried by the ram for actuating the ram to direct material into a cushion cover.
2. A filling machine comprising a stand, a box and a platform carried by the stand, a pair of supports extending upwardly from the platform, each of said supports comprising a pair of closely related members, roller means confined between the members of the supports, a ram carried by the roller means and guided by said members, and means for actuating the ram to direct material placed in the box into a cushion cover adapted to be located at one extremity of the box.
3. A machine for filling a cushion cover comprising a stand, a box carried by the stand, a platform carried by the stand, a pair of supports on the platform, a ram slidably mounted on the supports, notches provided in the ram, a fitting slidably mounted on the ram, a lever pivotally connected to the fitting, means connected to the lever for causing the lever to forcibly engage and drive the ram in one direction, and a pawl carried by one of the supports for engaging a notch to prevent movement of the ram in an opposite direction each time the ram is driven a predetermined distance in said one direction, said one support providing a stop for the fitting.
4. A machine for filling a cushion cover comprising a stand, an elongated box carried by the stand, a platform carried by the stand and extending rearwardly thereof, supporting means mounted on the platform, a ram slidably mounted on the supporting means, a fitting slidable on the ram, a lever pivoted on the fitting, foot controlled means for operating the lever to cause it to forcibly engage and drive the ram in a step-by-step movement in one direction into the box, means for locking the ram at each step, and recess means formed on the ram for automatically rendering the locking means inoperative when the ram reaches a predetermined position in its travel in said direction.
5. A machine for filling a cushion cover comprising a stand, a box carried by the stand and extending forwardly thereof, a platform carried by the stand and extending rearwardly thereof, supporting means mounted on the platform, anti-friction means and bearings carried by the supporting means, a ram supported between and by the anti-friction means and bearings, a clutch carried by the ram, means for operating the clutch to drive the ram step by step into the box, means for automatically locking the ram at each step, means on the ram for rendering the locking means inoperative when the ram reaches its limit of travel in the box, and means for returning the locking means to a position to again lock the ram after the ram has been retracted to a limit of travel in the opposite direction.
6. Supporting means, a ram bar mounted on the supporting means for reciprocation, a fitting slideable on the bar, means connected to the fitting for engaging the underside of the ram bar for driving the ram bar step-by-step in one direction, a plurality of abutments on the upper side of the ram bar, locking means automatically selectively engageable with the abutments for holding the ram bar at each step, and notch means on the

ram bar for automatically rendering the locking means inoperative when the ram bar reaches its limit of travel so that the ram bar can be retracted to a starting position.

7. Supporting means, a ram bar mounted on the supporting means for reciprocation, means for progressively driving the ram bar in one direction, a plurality of abutments on the ram bar, locking means automatically selectively engageable with the abutments for holding the ram bar in place each time the ram bar is driven a predetermined distance in said direction, means for automatically rendering the locking means inoperative when the ram bar reaches its limit of travel so that the ram bar can be retracted to a starting position, and means for automatically rendering the locking means operative after the ram bar is retracted to the starting position 15 so that the ram bar will be held in place as before.

8. Supporting means, a ram bar carried by the supporting means, a row of notches provided in the ram bar, a pawl carried by the supporting means for selectively engaging the notches, a clutch carried by the bar and including means for actuating the clutch to operate the bar, and said bar having a recess adjacent each end of the row of notches, said pawl and recesses being so constructed and arranged that when the bar is moved in one direction by the actuating means the pawl will engage a notch to hold and prevent movement of the bar in an opposite direction and when the bar reaches a predetermined position of travel in said one direction the pawl will enter one of the recesses to permit the bar to be returned in the opposite direction to a starting position 20 in which position the pawl will automatically fall into the other recess so that the pawl will function to hold the bar against movement in said opposite direction when moved in said one direction.

9. A sub-assembly for use in filling a cushion cover with filler comprising supporting means, a bar slidably supported on said supporting means, a plurality of abutments on said bar, locking means on the supporting means engageable with the abutments for automatically holding the bar against movement in a direction opposite to that in which it is driven, means on the bar whereby the locking means is released when the bar reaches a predetermined driving position so that the bar can be retracted to a starting position, and means on the bar for causing the locking means to automatically return to a position where it may again become operative for holding as aforesaid when the bar is in said starting position.

10. A sub-assembly for use in a cushion filling machine comprising, a pair of standards, a spacer secured between the lower ends of the standards, a bearing secured between the upper ends of the standards, a roller mounted on the standards in spaced relation to the bearing, a ram bar arranged between and carried by said bearing and roller, longitudinally spaced abutments provided on the ram bar, and a locking means engageable with the abutments for automatically locking the ram bar in place when moved in one direction.

11. A sub-assembly for use in a cushion filling machine comprising a mounting, a pair of spaced upright supports connected to the mounting, anti-friction means on each support, a ram bar supported on said anti-friction means, a locking means on one of the supports for locking the ram bar in place when moved in one direction, a fitting slidably mounted on the ram bar, a lever pivoted on the fitting, and means operatively connected

to the lever for causing the lever to forcibly engage and drive the ram bar on the anti-friction means.

5 12. A machine for filling the cover of a cushion comprising a stand, a pair of rods on said stand, a box having a bottom wall fixed on said stand and a pair of side units mounted on the rods for movement relative to the bottom wall for varying the width of the box, each of said side units including a portion overlapping said bottom wall and cooperating therewith to form the bottom of the box, a platform mounted on the stand, a pair of upright supports secured to the platform, a rack bar carried by the supports, a pressure plate attached to one end of the bar, means for driving the rack bar, and a gravity operated pawl engageable with the rack bar for locking the bar in place when desired.

13. A machine for filling the cover of a cushion comprising an elongated mounting, a hanger carried by the mounting, a pair of longitudinally spaced supporting means extending upwardly from the mounting, a ram assembly carried by the supporting means, means for actuating the ram assembly, and means for operating the actuating means, said operating means including a generally triangular frame having one corner pivotally mounted on the hanger, a pair of links connecting the actuating means with a second corner of the frame, a treadle, and means connecting the treadle with a third corner of the frame.

20 14. A mounting, a pair of supports on the mounting, a ram slidably mounted on the supports, abutments provided on the ram, a fitting slidably mounted on the ram, a lever pivoted on the fitting, means for operating the lever to cause it to engage and drive the ram forwardly step by step, a pawl carried by one of the supports for engaging an abutment to prevent rearward movement of the ram as it is advanced forwardly, and one of said supports serving as a stop for the fitting.

25 15. A sub-assembly for use with a cushion filling machine comprising a pair of spaced upright supports for connection with a mounting, anti-friction means on each support, a ram bar supported on said anti-friction means, said ram bar being provided with a plurality of spaced abutments and a recess, a locking means on one of the supports for selectively engaging the abutments for locking the ram bar in place as it is driven in one direction, means for driving the ram bar, and said recess being deeper than the notches and serving to render the locking means inoperative when the locking means is disposed therein.
